CLAIM

We claim the ornamental design for an air canning rack, as shown and described.

DESCRIPTION

FIGS. 1-8 illustrate a first embodiment of the air canning rack in which:

FIG. 1 is a perspective view showing the air canning rack within the context of an example environment, wherein example canning jars are received therein;

FIG. 2 is a perspective view of the air canning rack;

FIG. 3 is a left side view thereof;

FIG. 4 is a front view thereof;

FIG. 5 is a right side view thereof;

FIG. 6 is a rear side view thereof;

FIG. 7 is a top view thereof; and

FIG. 8 is a bottom view thereof.

FIGS. 9-15 illustrate a second embodiment of the air canning rack in which:

FIG. 9 is a perspective view of the air canning rack;

FIG. 10 is a left side view thereof;

FIG. 11 is a front view thereof;

FIG. 12 is a right side view thereof;

FIG. 13 is a rear view thereof;

FIG. 14 is a top view thereof; and,

FIG. 15 is a bottom view thereof.

Broken lines are used in the drawings to illustrate environment or features of the air canning rack that form no part of the claimed design.
